UNITED STATES PATENT OFFICE.

HENRY JOSEPH CARY, OF SAUKVILLE, WISCONSIN.

OIL BURNER.

Application filed January 20, 1927. Serial No. 162,305.

This invention relates to oil burners. In oil burners as heretofore constructed, it has been found that a great amount of roaring occurs and that although attempts have been made to minimize this roaring by placing obstructions or a foreign substance in the generator tube, that nevertheless the roaring continues to an objectionable degree in burners prior to this invention.

10 Further, in the burners as heretofore constructed, the generating tube rapidly carbonizes and clogs and, consequently, materially interferes with the action of the burner.

In addition to this, burners constructed 15 for the use of oil are of the general type in which a spider web is used, or, in which a multitude of apertures are provided in the upper portion. This construction is difficult to make and does not operate satisfactorily.

20 This invention is designed to overcome the above noted defects, and objects of such invention are to provide an oil burner such, for example, as a kerosene oil or gasoline burner, which is so constructed that it will operate 25 quietly without roaring and with a steadiness heretofore considered impossible with oil burners.

Further objects are to provide a unique 30 construction of generator in which the heavier liquid, namely, oil, is made to climb up hill, thereby giving the oil which has been changed into a vapor opportunity to pass out through the small jet orifice, thereby eliminating pulsation.

35 Further objects are to provide a novel form of oil burner in which the generating tube is free from obstruction from one end to the other, and yet which does not roar or pulsate and which is free from carbonizing and 40 clogging.

Further objects are to provide an oil 45 burner having a generating tube which slants upwardly and which has different zones or portions thereof maintained at different temperatures, and to so construct the burner that these temperatures are constant and do not fluctuate and are graded from that having the lowest temperature at the point where the oil enters to that having the 50 highest temperature adjacent the point at which the gas passes to the control valve or needle valve.

Further objects are to construct a novel 55 form of burner with a minimum number of

parts and having the characteristics enumerated above and to so form the upper or main baffle plate that the flame and heated products of combustion are caused to play about or lap about the generator tube, and are held in predetermined positions so that the different zones of temperature of the generator tube are maintained, and yet to provide a construction which is extremely simple, which is highly practical and which may be easily produced.

60 Further objects are to provide a novel relation between the mixing tube and the open body of the burner where the gas and air are distributed to the apertured portion at which the flame forms, so that the maximum mixing occurs, and yet in which a minimum restriction to the flowing combustible mixture is occasioned.

65 Further objects of this invention are to provide a novel form of burner in which three main portions, preferably of cast material are provided, namely, a bottom body portion, a head, and a baffle member or flame director, and to provide means whereby the starting cups may be formed of sheet metal so and readily attached to these main members, so that relatively simple castings are required for this burner.

70 A further object of this invention is to provide a novel form of burner in which the head is adjustable without dismantling the burner, so that the exact degree of spacing between the body portion and the head may be most easily secured by simple adjustments after the burner has been assembled, to give 75 a flame having the proper combustion.

80 An embodiment of the invention is shown in the accompanying drawings in which:

Figure 1 is a plan view thereof with parts broken away;

Figure 2 is a view similar to Figure 1 showing the baffle member or flame director removed;

Figure 3 is a side elevation of the burner;

Figure 4 is a sectional view on the line 85 4-4 of Figure 1;

Figure 5 is a sectional view on the line 90 5-5 of Figure 1;

Figure 6 is a sectional view on the line 6-6 of Figure 3;

Figure 7 is a sectional view on the line 95 7-7 of Figure 1;

Figure 8 is a sectional view through the

forward portion of the flame director approximately on the line 8-8 of Figure 3.

Referring to the drawings, it will be seen that the burner comprises a main body portion 1 which has an integral mixing chamber 2 formed therein. The mixing chamber 2 stops at the point indicated by the reference character 3 in Figure 2 a material distance from the inner peripheral surface or 10 wall 4 of the body portion. The body portion, it will be noted, has a circular cavity 5 defined by the wall 4 and into which the combustible mixture flows from the mixing chamber 2. It is to be noted, particularly 15 from Figures 2 and 4, that the cross sectional area of the mixing tube is approximately equal to one-half of the combined areas in the chamber 5 on opposite sides of such mixing tube. This has been found in actual 20 practice to be eminently satisfactory and to aid in the accurate distribution of the flame and also in the quietness of operation. This body portion is supported in any suitable manner, as by means of a downwardly extending apertured lug 6. It carries a supply 25 head 7 adjacent its forward side, such head 7, as may be seen from Figure 2, being detachably secured in place by means of screws 8 passing therethrough and threaded 30 into the body portion. As shown from the sectional view, Figure 6, the main body portion 1 carries a downwardly opening channel protecting member 9 which is formed of sheet metal and is detachably secured by 35 means of a screw 10 passing through an apertured lug formed in the member 9. A channel-shaped metal shell 9' is slidably mounted upon the member 9 and may be moved up or down to give the proper air 40 opening for oils of different densities, such for instance, as kerosene or gasoline. This protecting member or protecting baffle admits the air from the underside of the burner, as may be seen from Figure 4, and protects the entrance to the mixing chamber 2 from any flame or other disturbance, and also it has been found, aids in the quietness 45 of operation of the device. For instance, as shown in Figure 4, a pressed metal starting cup or heating cup 11 is positioned just below the head 7 and outside of the protecting baffle plate or channel member 9. Preferably, this pressed metal starting cup is carried by a screw 12 passing into the head 7. 50

The head 7, it will be noted from Figure 4, is provided with an adjusting screw 13 controlled by a hand wheel 14. This screw constitutes in effect a needle valve rod and controls the needle valve 15 (see Figure 4) 55 which in turn controls the gas flow through the gas nozzle 16.

The head 7 is provided with a generating tube 17 that slants upwardly from the oil inlet end 18 (see Figure 3) to the downwardly extending discharge end 19 which

latter end leads directly to the head 7, as may be seen from Figures 3 and 4. This generator tube is unobstructed, as may be seen from Figures 4 and 7, and as previously mentioned, slants upwardly in a gradual 70 manner from the inlet to its outlet end.

Above the main body portion 1, a head 20 is positioned. This head, as may be seen from Figures 1 and 4, is disc-like and rests in a depression 21 formed in the body portion 75 1. It is provided with a plurality of small lugs 22 to determine the minimum spacing between the head and the body portion. However, as may be seen from Figures 3 and 6, the body portion is provided with 80 three screws 23 which extend upwardly therethrough and which contact with the lower or bottom face of the head 20 as may be seen from Figure 3. Thus, by adjusting the screws 23 the height of the head 20 from the body portion may be accurately adjusted after the burner has been assembled, so that the maximum efficiency and correct distribution of the combustible mixture and necessarily, the resulting flame, is obtained. A 90 central screw 24 is provided which slidably receives and holds the head 20 in its correct position with its peripheral portion spaced from the corresponding wall of the body portion. If desired, the head 20 may be 95 clamped between the screws 23 and the screw 24 when the correct adjustment has been obtained. Preferably, the head 20 is provided with a plurality of tongues 25 (see Figure 1) which fit within and are spaced 100 from the walls of radial depressions or recesses 26 formed in the body portion 1.

Above the body portion 1, a main deflector 27 is positioned. This deflector is provided with a shouldered groove 28 which 105 seats upon the edge of the body portion, as shown in Figure 4, and thus correctly positions the deflector. It is to be noted that generally this deflector has its outer walls slanting upwardly towards its open central portion so as to cause a slight convergence of the resulting annular flame. However, it is to be particularly noted that the deflector 27 is cut away, as indicated at 29 in Figure 8, adjacent the end 19 of the generating tube and that it is provided with a short inwardly positioned wall 30 which directs the flame outwardly towards the generating tube. The flame is caused to wrap around the portion 19 of the tube by means of an 110 outwardly projecting arm 31 formed integral with the deflector and extending around the portion 19 of the tube, as shown in Figures 1, 3, 6 and 8.

It is to be noted further from Figures 1, 125 3, and 5, that the deflector is provided with a downwardly extending tongue or lip 32 which wraps over the generator tube 17 intermediate its uppermost end and the entrance end 18. This lip 32, therefore, causes 130

the flame or heated products of combustion to wrap around the generator tube and maintain the proper temperature thereof in this zone.

From the construction thus far described, it is clear that the flame or highly heated products of combustion are caused to act upon the generator tube in a predetermined manner and are held in such positions with reference to the tube against any fluctuations or variations due to air currents or other disturbances. It will be seen further that the generator tube is coolest at the entrance end 18 and is heated in different zones to gradually increase in temperatures as the extreme end or the delivery end of the generating tube is approached.

Further, it will be seen that the generator tube, due to its upward slant, maintains a predetermined level for the oil corresponding to a given demand upon the burner. If, for any reason, the gas pressure should increase in the generator tube, the oil is forced back down the tube along its slanting portion until a correct balance is obtained between the pressure and the height of the oil. This adjustment is wholly automatic and as the generator tube is free from obstructions, such adjustment will take place with the utmost facility.

Further than this, carbonizing does not result as the oil is backed away from the most highly heated portions of the generator tube and only comes in contact with the heated portions thereof in a gradual manner; that is to say, approaching through the lowest temperature zones towards the highest temperature zones so that vaporization takes place without any high heating of the oil and, consequently, without carbonization. The gases are heated to the desired extent by the means described in detail above.

In order to quickly secure an initial heating of the generator tube, an elongated starting cup 33 (see Figures 1 and 3) is provided immediately below the generator tube. This starting cup, as may be seen from Figures 1, 2, 5, 6, and 7, is formed of sheet metal and may be attached in any suitable manner, as by means of the screw 34 (see Figure 5). This starting cup similar to the generator tube is arranged approximately tangentially to the general outline of the body portion 1, as shown most clearly in Figures 1 and 6. However, it is to be noted that these members are tangent to the general outline of the body portion at different points so that they are arranged at a slight angle to each other. As may be seen from Figure 1, the advantage of this construction resides in the fact that the outermost end is exposed and permits the ready filling of the starting cup. Further, the innermost end extends inwardly beneath the overhang-

ing lip or flange 32 and thus when the contents of the cup is lighted, the flame is caused to wrap around the generator tube and quickly bring it to the desired temperature.

In operation, it has been found that this burner produces a quiet, intensely hot flame and a flame which is very evenly distributed and free from soot.

Further, it has been found from actual tests conducted with this device that the generator tube does not carbonize, but maintains a substantially clean interior surface throughout a prolonged period of use.

It has been found further that the objectionable roaring heretofore experienced with burners employing generating tubes, has been wholly eliminated and also the roaring at the burner itself has been avoided.

Further, it is to be noted that the generator tube provides a free passage as it has been unnecessary to fill this tube with any obstructing material, as has heretofore been found necessary.

It will be seen further that a perfectly designed generator unit has been provided which is detachably held in place by two screws and may thus be applied to different size burners.

The burner also has been found to operate with the utmost steadiness and to be affected to a minimum extent by drafts and undesirable currents of air. The openings and exits for the air and mixture are so arranged that they are shielded and are not affected by transverse air currents.

Further, it will be seen that the castings required for this burner are extremely simple and may be very readily produced. Further, due to the detachable fuel head which carries the adjusting valve, one of the starting cups, and the generator tube outlet, an easy machining is obtained.

Further than this, the construction is such that pressed metal starting cups may be easily attached, as described in detail above, and consequently the cost of production materially reduced.

Although the invention has been described in considerable detail, such description is intended as illustrative rather than limiting as the invention may be variously embodied and as the scope of such invention is to be determined as claimed.

I claim:

1. An oil burner comprising a main head having a mixing compartment a gas nozzle for directing fuel into said compartment, an upwardly slanting generator tube for conducting fuel to said nozzle, and a flame director mounted above said main head and having outwardly extending curved lips for deflecting the flame towards said generator tube, one of said lips extending over said

generator tube and slanting upwardly towards the delivery end of said tube, said lips partially curving around said generator tube for causing the flame to wrap around said generator tube to a greater and greater extent as the discharge end of said generator tube is approached.

2. An oil burner comprising a main head having a mixing compartment, a gas nozzle for directing fuel into said compartment, an upwardly slanting generator tube for conducting fuel to said nozzle, and a flame director mounted above said main head and having outwardly extending curved lips for

deflecting the flame towards said generator tube, one of said lips extending over said generator tube and slanting upwardly towards the delivery end of said tube, another of said lips extending around the delivery end of said generator tube, both lips directing the flame towards the delivery end of said tube.

In testimony that I claim the foregoing I have hereunto set my hand at Milwaukee, in the county of Milwaukee and State of Wisconsin.

HENRY JOSEPH CARY.
